UNITED STATES PATENT OFFICE.

WILLIAM J. STRENG, OF DETROIT, MICHIGAN.

WHEELED CHAIR.

SPECIFICATION forming part of Letters Patent No. 617,058, dated January 3, 1899.

Application filed October 15, 1898. Serial No. 693,636. (No model.)

To all whom it may concern:

Be it known that I, WILLIAM J. STRENG, a citizen of the United States, residing at Detroit, in the county of Wayne and State of Michigan, have invented certain new and useful Improvements in Wheeled Chairs, of which the following is a specification, reference being had therein to the accompanying drawings.

- 10 The invention consists, first, in the adjusting means for the back and foot-rest sections; further, in the construction of said foot-rest section; further, in the construction of the running-gear frame, and, further, in the construction, arrangement, and combination of parts, as more fully hereinafter described and claimed.

In the drawings, Figure 1 is a perspective view of my wheeled chair. Fig. 2 is a side elevation thereof with the wheels removed. Fig. 3 is a section showing the clamp for the back and foot-rest adjustment.

A is the seat-section, to the front and rear edges of which are hinged, respectively, the 25 foot-rest section B and the back-section C. These three sections are adjustably secured together by means of the bars D, arranged on opposite sides of the chair. Each bar D is pivoted at its upper ends a to the back-section, and at its lower end is provided with a curved and longitudinally-slotted section b, slidingly engaging with pivot-pins c on the foot-rest section. Intermediately the bar D is provided with a longitudinal slot d, with 35 which a clamping pivot-bolt E on the seat-section engages, preferably a single bolt passing transversely through the seat and slots d of each rod and provided at each end with clamping-nuts F. These nuts F are preferably in the form of knobs or wheels, which may be easily grasped and operated by the user of the chair while seated therein.

The length of the slots d is sufficient to permit of swinging the back through the desired 45 angle of adjustment, the clamping-bolt and nuts serving to lock it at any point. The movement of the back will, through the engagement of the curved slotted sections b of the bars d with the pins c, cause a corresponding movement of the foot-section B, the bars D sliding and twisting on the bolts E.

The upward swinging of the foot-section is

greatly facilitated by the curved form of the slots with which the pins c engage, as the pressure on the pin is brought more nearly 55 in the direction of its movement. Thus when the seat-section is in substantially a vertical position and the pins are at the inner ends of the slots the pressure on the pins is more forward than upward; but as the section 60 swings forward and the pins travel forward in the slots the pressure becomes more of a lift.

G are brackets secured to the sides of the foot-rest section B and comprising the parallel bars e and f, the former being provided with a series of notches g and the latter with a corresponding series of lugs or shoulders h.

H is a footboard or shelf the ends of which 70 are reduced in width and are adapted to enter the slot between the bars e and f, one edge engaging with one of the notches g and the other resting upon the corresponding lug or shoulder h. With this construction the 75 height of the footboard H may be changed by turning it at an angle so as to disengage its rear edge from the notch g and to engage it with a higher or lower notch and then turning it back again to rest its forward edge on 80 the lug h.

The seat-section A is supported upon the axles I and J for the forward and rear wheels K and L, respectively, the forward wheels being small and the rear wheels of greater 85 diameter.

The supporting-frame preferably comprises the following construction: M is a spring-bar, at its forward end connected to the axle I, which bar has the upwardly and rearwardly 90 extending portion i attached to the bottom of the seat at a point near its rear edge. Beyond this point of attachment the bar is formed into a spiral curve j, extending around the rear axle J and having its end secured to 95 said axle.

N is a reach-bar connected at its rear end with the end of the bar M to the axle J and at its forward end riveted or otherwise secured to the portion i of the bar M.

O is a vertical bar or post secured at its lower end with the bar M to the axle I and at its upper end to the bottom of the seat near 100 its forward edge.

A wheeled chair of the construction above described is especially adapted to be employed as a child's carriage, the adjustable feature of the back and foot-rest permitting of its being thrown into any suitable form or inclination that may be desired and the parts M, N, and O forming a light and springy frame. At the same time its use is not limited to this one purpose, and it is obvious that it might be employed as an invalid-chair capable of being propelled by the user by turning the large rear wheels by hand. For the latter purpose, the adjustment for the back and foot-rest being controlled by the clamping-knob F, which is in a most convenient position for operation by a person sitting in the chair, the inclination may be altered as often as desired with but little effort on the part of the user.

20 What I claim as my invention is—

1. The combination with the seat-section having the back and foot-rest sections hinged thereto, of a side connecting-bar D pivotally secured at its upper end to the back-section and having the central longitudinal slot d and the curved and slotted end section b, a pin c on said foot-rest section with which said slotted section b engages and a clamping-pivot on said seat-section engaging with said slot d and adapted to hold the parts in any position of adjustment.

2. The combination with the seat-section having the back and foot-rest sections hinged thereto of bars D pivotally secured at their upper ends to said back-section on opposite

sides thereof, each having a central, longitudinal slot d and a curved and slotted end section b, pins on said foot-rest section engaging with said slotted sections b, a rod E passing transversely across said seat-section 40 and the slots d of the bars, and clamping-nuts F engaging with the opposite ends of said rod.

3. The combination with the foot-rest section, an adjustable footboard therefor, of brackets G on opposite sides of said section, 45 comprising parallel bars between which the ends of said board project, one of said bars being provided with a series of notches g and the opposite bar with a corresponding series of lugs or shoulders h for the purpose de- 50 scribed.

4. A wheeled chair comprising a seat, the forward and rear wheeled axles and a supporting-frame comprising the bars M, each attached at one end to the forward axle and having the upwardly and rearwardly extending section i, secured to the bottom of the seat near its rear edge, and the spiral spring portion j passing around the rear axle and secured thereto, the reach members N connecting said rear axle with the portions i of the bars M and the posts O supporting the forward edge of the seat.

In testimony whereof I affix my signature in presence of two witnesses.

WILLIAM J. STRENG.
